ORE CONCENTRATING DEVICE

Philip H. Stevenson, Denver, Colo., assignor of
one-third to Philip A. Witt and one-third to
Geraldine A. Witt, both of Denver, Colo.

Application October 9, 1934, Serial No. 747,542

5 Claims. (Cl. 204—15)

This invention relates to an ore concentrating device, and has for its principal object the provision of a method and construction which will not only collect separate mineral values from ore pulp, but will simultaneously produce a flocculating chemical in the pulp during the separating phase so as to coagulate or precipitate the exceedingly fine suspended metallic values which are ordinarily carried away in suspension.

It is well known that aluminum hydroxide in solutions has the property of forming floccules which in settling carry down any suspended solids or other substances from the solution. It is also well known that a concentrating table as used in ore dressing has the property of settling and catching the heavier mineral values from flowing ore pulp.

This invention is designed to combine these two well known properties into a single unit so that the aluminum hydroxide will be produced immediately on a concentrating table to precipitate suspended values to the table riffles for collection.

Briefly this is accomplished by positioning energized electrodes of aluminum or aluminum alloy in the path of the flowing pulp upon the concentrating table, or in the path of the pulp to the concentrating table or both. In this way, the aluminum hydroxide is electrolytically produced at the very point where it is to be used, and is therefore in a highly efficient and nascent condition, resulting in an immediate and highly efficient action.

Other objects are to so construct the device that the electrodes will present a maximum active surface for electrolytic action; so that the electrodes can be easily removed and replaced when they become eaten away; so that short circuits and electrical break downs are avoided; and so that the electrodes will not interfere with the natural flow and table action.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:—

Fig. 1 is a plan view of a typical concentrating table to which the invention has been applied. Fig. 2 is a longitudinal section therethrough.

Fig. 3 is an enlarged fragmentary plan view of a portion of the table top. Fig. 4 is a detail section, looking toward the head end of the table, and taken on the line 4—4, Fig. 3. Fig. 5 is an enlarged detail section through the head end of the table, taken on the line 5—5, Fig. 4.

A typical concentrating table is illustrated at 10, with its water box at 11, feed launder at 12, tailings box at 13, concentrate box at 14, and head board at 15. Such a table is provided with a series of riffles 16 secured in parallel relation to a bottom of linoleum or similar material. Means, of course, are provided (though not shown) for vibrating or shaking the table when in operation.

The invention is applied to the table 10 by placing a series of insulating spacing discs 18 along the upper edge of the riffles 16 and placing metallic strips or bars, which will be herein designated as the anodes 19, thereon. The spacing discs 18 maintain the anodes a slight distance above and parallel to the tops of the riffles 16. Between each pair of riffles, a second metallic strip or bar, which will be herein designated as the cathodes 20, is placed and supported upon suitable insulating spacers 21.

The anodes 19, and the cathodes 20 are secured to the table by means of suitable screws 22 which pass through the strips, through the spacers, and into the linoleum table top 17. The anodes 19 are electrically connected together, preferably adjacent the head board 15, by means of a positive bus bar 23. The cathodes 20 are similarly connected by means of a negative bus bar 24. The bus bars 23 and 24 lead to any suitable generating equipment as indicated at 25.

It has been found that the table will operate satisfactorily on either alternating or direct current so that the terms "positive", "negative", "anode", and "cathode", as used herein, are simply used for convenient nomenclature and not to indicate direction of flow of the electrical current.

It is preferred to place a two series of laterally inclined bars 25 and 26 of aluminum or aluminum alloy at the feed side of the table in the path of the pulp flow. The bars 25 are connected to a collector bar 27, and the bars 26 are connected to a similar collector bar 28. The collector bars 27 and 28 are in turn connected to the bus bars 23 and 24, respectively.

It can be readily seen that when aqueous ore pulp is fed laterally across the table over the riffles 16, it will act as an electrolyte in which the

aluminum bars 19 and 20 will act as electrodes. This causes an electrolytic action which decomposes the aluminum metal of the bars into nascent aluminum hydroxide. The latter flocculates in the solution between the riffles and collects and precipitates all suspended metallic values which are caught and separated from the tailings by the riffles 16.

The bars 25 and 26 give a preliminary, electrolytic action serving to surcharge the solution with aluminum hydroxide before it reaches the riffles. This surcharging action can be still further enhanced by positioning a series of aluminum electrodes 29 in the feed launder 12, and connecting these with the source of current. The electrodes 29 are not riffles and may be placed in the flow in any desired manner.

The above construction has many advantages. First the open space below each of the strips allows the solution to flow under as well as over the electrodes so as to present a maximum amount of surface to the electrolytic action. Another advantage of this spaced-away construction resides in the fact that the eating away or electrolysis of the electrodes does not interfere with the collecting action of the riffles. If the bars were placed flat against the table, they would present only one side to electrolysis, would create an uncertain riffle action and as they became eaten away would create an uneven pulp flow to the detriment of the concentrating action of the table.

While preferred forms of the invention have been described in some detail together with the theories which it is believed to best explain its success, it is to be understood that the invention is not limited to the precise procedure described nor is dependent upon the accuracy of the theories which have been advanced. On the contrary, the invention is not to be regarded as limited except in so far as such limitations are included with the terms of the accompanying claims in which it is the intention to claim all novelty inherent in the invention as broadly as is permissible in view of the prior art.

Having thus described the invention, what is claimed and desired secured by Letters Patent is:—

1. An ore concentrating device comprising: a

surface for receiving an aqueous pulp of the ore to be concentrated; a series of aluminum electrodes spaced from said surface in the path of said pulp; and means for furnishing electrical current to said electrodes, said electrodes comprising: relatively long metallic strips insulated and spaced from said surface; adjacent strips in said series being connected to opposite poles of said current furnishing means.

2. In an ore concentrating table having a series of spaced-apart riffles, means for electrolytically producing an aluminum hydroxide adjacent said riffles comprising: a metallic strip extending along each of said riffles; means for furnishing electrical current to said strips; and insulating spacers supporting said strips in spaced relation to said riffles.

3. A riffle construction for concentrating tables comprising: a series of spaced apart, parallel, tapered riffles secured to said table; an aluminum strip above each of said riffles; spacing members spacing said strips from said riffles; means for securing said strips to said riffles; and means for connecting said strips to a source of electric current.

4. A riffle construction for concentrating tables comprising: a series of spaced apart, parallel, tapered riffles secured to said table; an aluminum strip above each of said riffles; spacing member spacing said strips from said riffles; means for securing said strips to said riffles in combination with a second series of metallic strips, each strip of said second series being positioned below the first strips between a pair of said riffles; means for spacing said second series above said table; and means for connecting said two series of strips to opposite poles of a current source.

5. A riffle construction for concentrating tables comprising: a series of spaced apart, parallel, tapered riffles secured to said table; an aluminum strip above each of said riffles; spacing members spacing said strips from said riffles; means for securing said strips to said riffles, there being fluid passages between said strips and said riffles so that solution may flow beneath said strips and over said riffles; and means for connecting said strips to a source of electric current.

PHILIP H. STEVENSON.
